UNITED STATES PATENT OFFICE.

JESSE ALEXANDER, OF NEW YORK, N. Y., ASSIGNOR OF ONE-HALF TO CHARLES B. NICHOLS, OF NEW YORK, N. Y.

TYPE-WRITING-MACHINE RIBBON-OPERATING MECHANISM.

1,091,179.

Specification of Letters Patent. Patented Mar. 24, 1914.

Continuation of application Serial No. 664,760, filed December 9, 1911. This application filed April 14, 1913. Serial No. 760,978.

To all whom it may concern:

Be it known that I, JESSE ALEXANDER, a citizen of the United States of America, and residing at New York, in the county of 5 Kings and State of New York, have invented new and useful Improvements in Type-Writing-Machine Ribbon-Operating Mechanism, of which the following is a specification.

10 My invention relates particularly to front stroke or visible writing machines. In machines of this character the ribbon is usually carried by two spools on opposite sides of the machine and a portion of the ribbon is raised in front of the printing type at each stroke of the keys. This lifting is done by some form of universal bar action. Then after the stroke of the type the ribbon is fed a short distance so as to bring a fresh surface in front of the next type. This feeding is usually accomplished by means of the universal bar action. The power for shifting and feeding the ribbon is thus derived from the key action.

20

25 It is my object to decrease the power consumed in the key action and to provide a simple and yet reliable mechanism.

Another object is to provide a simple means for reversing the direction of the feed 30 of the ribbon and means for holding the spools in place.

Briefly considered the invention contemplates the feeding of the ribbon by the same mechanism which feeds the carriage that is, the tension drum. The ribbon spools are carried by vertical shafts having bevel gears at the lower ends. These bevel gears are driven by bevel pinions carried by horizontal shafts. Each horizontal shaft is in two parts adapted to be connected by means of a clutch, one part of one shaft is connected to the carriage feeding drum. The two shafts are connected by a suitable belt, cord or chain. A slide having forked cam members 45 is adapted to throw the clutches on the two shafts into and out of engagement so as to reverse the direction of feed of the ribbon. The cross-slide is operated by a push rod from the front of the machine. The shifting of the ribbon to the printing point is accomplished by the universal bar action.

The principles of the invention will be understood from the following specification

and the accompanying three sheets of drawings.

Figure 1, is a vertical longitudinal section of a machine showing the parts embodying the improvements of my invention. Fig. 2, is a front view of the carriage feeding drum showing the pawl and ratchet for driving the ribbon feed. Fig. 3, is a plan view of a machine embodying the improvements of my invention, the carriage being omitted. Fig. 4, is a vertical sectional view on the plane of the line X X of Fig. 3 taken from the rear. Fig. 5, is a detail view of one of the clutches. Fig. 6, is a sectional view of one of the driving shafts and its clutch.

The carriage 1 travels from side to side of the machine on the front track 2 and the rear track 3 being impelled toward the left by a suitable form of tension drum 4 and tension band 5. The step by step movement from right to left may be controlled by any suitable form of escapement (not shown).

The form of key and type bar mechanism illustrated herein is claimed in another application #760,979 filed herewith but any suitable form may be employed as the ribbon mechanism is independent of the particular construction of key and type bar mechanism. The type bars such as 6 are carried by a type bar plate 7 and adapted to strike against the front of the platen 8. The key levers such as 9 are pivoted in any suitable manner and connected to operate the type bars. The intermediate lever 10 which is connected to the key lever 9 is under tension of a spring 11 and its upper end is pivoted to the link 12. This link is connected to a toothed disk 12' which engages the type bar 6.

The ribbon 13 has its opposite ends attached to the spools 14 and 15 mounted respectively on the shafts 16 and 17. Adjacent the printing position the ribbon is supported by a forked guide 18 which is adapted to be shifted vertically. This shifting is accomplished by the action of the key levers. The lower end of the guide 18 is connected to the front end of the lever 19 and the rear end of the lever is connected by a link 20 to the universal bar 21 which extends beneath the fingers such as 22 of the key levers. At the depression of any key lever the universal bar 21 is depressed and the lever 19 tilted so

as to shift the guide 18 upward and carry the ribbon in front of the printing position. When the key lever 9 is released the spring 11 tends to pull the intermediate lever 10 and thus raises the key lever to its normal position raising with it the universal bar 21 and thus retracting the ribbon guide 18.

The bevel gear 25 on the lower end of the shaft 16 meshes with bevel pinion 26 on the shaft 27. The shaft 28 in alinement with shaft 27 has a ratchet wheel 29 mounted adjacent the tension drum 4. A pawl 30 is pressed against the ratchet 29 by a spring 31. When the carriage is moved from left to right of the machine by hand, the drum 4 is rotated in a right-handed or clockwise direction and wound up, the pawl 30 slipping over the teeth of the ratchet 29. As the carriage is fed from right to left step by step under the control of the escapement, (not shown) the ratchet 29 and shaft 28 are rotated in a left-handed or anti-clockwise direction. On the adjacent ends of the shaft sections 28 and 27 is mounted a clutch member in the form of a sleeve 32. A pin 33 which extends through the shaft 28 fits loosely in a slot 34 in the sleeve 32. The front end of the sleeve 32 has one or more notches, such as notch 35, which in the position shown fits a pin 36 in the shaft 27. A driving connection is thus established between the tension drum 4 and the bevel pinion 26 so as to rotate the ribbon spool 14 in a left-handed or anti-clockwise direction as shown by the arrow in Fig. 3. A helical spring 37 presses against the sleeve 32 and against the collar 38 which is fastened on the shaft 28. The spring thus holds the clutch sleeve 32 forward in engagement with the pin 36 on the shaft 27. On the right-hand side of the machine is a shaft formed in two parts 40 and 41 adapted to be connected by a clutch 42 similar to clutch 32 just described. The two shafts 28 and 40 are connected by a cross belt, cord or chain 43 so as to rotate in opposite directions.

On the back of the type bar plate is mounted a rod 44 adapted to slide in order to reverse the ribbon feed. The clutches 32 and 42 have cam-like members 39 and 45 respectively. The bar 44 has projecting forks or fingers 46 and 47 adapted to coöperate with the members 39 and 45 respectively. When the parts are in the position shown, the cam 45 and clutch 42 are held in what may be termed the disengaged position so that there is no connection between the shaft 40 and the right-hand ribbon spool. To reverse the feed bar 44 is simply to move to the right (Fig. 3) so that the shoulder 46 engages the cam 39 and disengages the left-hand clutch. At the same time the shoulder 47 is freed from the cam and the right-hand clutch is brought into operative engagement. The reversal of feed may be accomplished in

a simple and convenient manner by means of the push rod 50 which extends through the front plate 51 of the machine and has an inclined portion 52 at the rear adapted to operate in an opening 53 in the bar 44. When the rod 50 is pulled outward as viewed in Fig. 3 the bar 44 will slide to the right and the bar 44 may be again shifted to the left by pushing in the rod 50.

Each of the ribbon spools is detachably mounted on its shaft being held in place by a latch 60 which overstands the lower flange of the spool. This latch is yieldingly held in position by a spring 61. The latch may be retracted by pressing upon the finger-piece 62 so that the spool may be taken off. The upper end 63 of the latch is inclined so that a spool may be put in place by simply pressing it down on its shaft, the edge of the lower flange of the spool engaging the end 63 of the latch and retracting it sufficiently to enable the flange to snap into place.

This application is a continuation of #664,760 filed December 9, 1911.

What I claim is:—

1. In a typewriter ribbon operating mechanism, two spool shafts, a two-part driving shaft geared to each spool shaft, a clutch for connecting the parts of each driving shaft, an operating connection between said driving shafts, a shifting bar for operating said clutches and a rearwardly projecting push rod having one end accessible at the front of the machine and having its rear end beveled to engage the shifting bar for the purpose specified.

2. In a typewriter ribbon operating mechanism, a vertical spool shaft, a driving shaft formed in two parts, one part being geared to said spool shaft, power means for rotating the other part of said shaft, a sliding clutch for connecting the two parts of said shaft, a transversely movable bar having a shoulder for moving said clutch and a rearwardly projecting push rod having a finger-piece at the front end and an inclined shoulder at the rear engaging said bar for moving it.

3. In a typewriter ribbon operating mechanism, a spool shaft, a two-part driving shaft having one part geared to said spool shaft, a sleeve-like clutch for connecting the parts of said driving shaft, an annular cam shoulder carried by said clutch and a transversely movable forked member for engaging said cam shoulder for moving said clutch member.

4. In a typewriter ribbon operating mechanism, a spool shaft, a two-part driving shaft having one part geared to said spool shaft, a sleeve-like clutch for connecting the parts of said driving shaft, an annular cam shoulder carried by said clutch, a transversely movable forked member for engaging said cam shoulder for moving said

clutch and a spring for opposing the movement of said clutch member.

5. In a typewriter ribbon operating mechanism, a spool shaft, a two-part driving shaft having one part geared to said spool shaft, a sleeve-like clutch for connecting the parts of said driving shaft, an annular cam shoulder carried by said clutch, a transversely movable forked member for engaging said cam shoulder for moving said clutch member and a rearwardly projecting push rod for moving said forked member.

6. In a typewriter ribbon operating mechanism, a tension drum, a pawl carried thereby, a ratchet to be driven by said pawl, a two-part shaft having one part driven by said ratchet, a clutch for connecting and disconnecting the parts of said shaft and a ribbon spool shaft geared to the other part of 20 said two-part shaft.

7. In a typewriter ribbon operating mechanism, a tension drum, a pawl carried thereby, a ratchet to be driven by said pawl, a two-part shaft having one part driven by 25 said ratchet, a clutch for connecting and disconnecting the parts of said shaft, a ribbon spool shaft geared to the other part of 30 said two-part shaft, a second spool shaft, a second two-part shaft and clutch and a driving connection between said two-part shafts.

8. In a typewriter ribbon operating mechanism, a tension drum, a pawl carried thereby, a ratchet to be driven by said pawl, a two-part shaft having one part driven by 35 said ratchet, a clutch for connecting and disconnecting the parts of said shaft, a ribbon spool shaft geared to the other part of 40 said two-part shaft, a second spool shaft, a second two-part shaft and clutch, a driving connection between said two-part shafts and a clutch operating member.

9. In a typewriter ribbon operating mech-

anism, ribbon spool shafts, two-part shafts each having one part geared to a spool shaft, a driving connection between the other parts, a tension drum having a pawl and ratchet connection with one of said other parts, and clutches for connecting the parts of said shafts.

10. In a typewriter ribbon operating mechanism, ribbon spool shafts, two-part shafts each having one part geared to a spool shaft, a driving connection between the other parts, a tension drum having a pawl and ratchet connection with one of 55 said other parts, clutches for connecting the parts of said shafts and a transversely movable bar for operating said clutches.

11. In a typewriter ribbon operating mechanism, ribbon spool shafts, two-part 60 shafts each having one part geared to a spool shaft, a driving connection between the other parts, a tension drum having a pawl and ratchet connection with one of 65 said other parts, clutches for connecting the parts of said shaft, a transversely movable bar for operating said clutches and a longitudinally movable push rod for operating said bar.

12. In a typewriter ribbon operating 70 mechanism, ribbon spool shafts, two-part shafts each having one part geared to a spool shaft, a driving connection between the other part, a tension drum having a pawl and ratchet connection with one of 75 said other parts, clutches for connecting the parts of said shafts, a ribbon lifting guide and a key-operated universal bar for shifting said guide.
